UNITED STATES PATENT OFFICE.

JOEL SIMPSON BLACKBURN, OF SALT LAKE CITY, UTAH TERRITORY.

TRUSS.

SPECIFICATION forming part of Letters Patent No. 415,087, dated November 12, 1889.

Application filed June 13, 1889. Serial No. 314,096. (No model.)

To all whom it may concern:

Be it known that I, JOEL SIMPSON BLACKBURN, a citizen of the United States, residing at Salt Lake City, in the county of Salt Lake 5 and Territory of Utah, have invented certain new and useful Improvements in Trusses; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to trusses, and has for its object to devise a simple and convenient means for securing the pad to the band, whereby said pad can be quickly adjusted on the band both laterally and at any relative 20 angle to meet the wants of the patient, and which will admit of the pad being fastened without possibility of injuring the patient by slipping of the tool used for tightening the pad.

25 The improvement consists of the novel features which will be hereinafter more fully described and claimed, and which are shown in the accompanying drawings, in which—

Figure 1 is a perspective view of a truss 30 embodying my invention. Fig. 2 is a horizontal section through the pad, showing the means for securing it to the band. Fig. 3 is a cross-section on the line X X of Fig. 2. Fig. 4 is a perspective view of the connecting-bar. Fig. 5 is a perspective view of the coupling. Fig. 6 is a perspective view of the steel dog. Fig. 7 is a perspective view of the clamping-screw cap. Fig. 8 is a reverse side view 35 of the plate, showing the spring.

40 The spring truss-band A is of ordinary construction, having the straight portion a in its rear, which portion is round and designed to receive the pads C C, each being secured thereto in a similar manner. The connecting-bar D, having head d at one end and the opening d' at the other end, is held to the pad by the plate B. The spring b between the pad and the connecting-bar is seated in a recess i in the pad, as shown, and permits 45 the pad to yield and exert a gentle and constant pressure on the hernia. The inner end 50

of this spring b passes through the opening d' and through a slot j in the tubular projection J on the rear side of the plate B. The connecting-bar works snugly in this tubular 55 projection, and is guided in its movements thereby, and is prevented from turning or pulling out by the end of the spring b, which passes through the opening d in the said bar D. The coupling E has slots e in its sides to 60 receive the band A, and is externally threaded at said slotted end to receive the screw-cap G. The steel dog F, inserted in the slotted end of the coupling, is of such length as to project slightly beyond the end of the coupling, to be engaged by the inner end of the 65 screw-cap, so as to be forced against the band A and clamp the same between the inner end of the dog and the head d' of the connecting-rod D. The inner end of the dog is depressed 70 to fit around the band, and is provided with the sharpened rib f between its sides to bite into the band A when the cap G is screwed home. The cap G has openings g, which are designed to receive the prongs h of the safety 75 screw-driver H, so that the latter cannot possibly slip and do injury to the patient when loosening or tightening the said cap. The connecting-rod passes loosely through openings in the plate B and in the closed end of 80 the coupling E, being held from displacement by the heads d and d'. When the cap G is removed, the dog F will drop out and the pad can be removed from the band. To adjust 85 the pad on the band, the cap G is loosened and the pad moved and turned on the band until the required adjustment is effected, when the screw-cap G is tightened and the position of the pad fixed.

Having thus described my invention, what 90 I claim, and desire to secure by Letters Patent, is—

1. The combination, with the band, the pad having the connecting-rod and the coupling, of the steel dog depressed to fit around the 95 band and having a sharpened rib f, and the screw-cap, substantially as described.

2. In a truss, the combination of the band A, the recessed pad, the connecting-rod D, having a head at each end, the plate B, spring b, coupling E, having slots e, steel dog F, having depressed end and sharpened rib f, and

the screw-cap G, having opening *g* to receive the prongs of an operating-tool, substantially as set forth.

3. The combination, with the pad and the connecting-bar D, having opening *d'*, of the plate B, having the slotted tubular projection, and the spring *b*, having its inner end passing through the slot in said tubular projec-

tion and through the opening *d'*, substantially as and for the purpose described. 10

In testimony whereof I affix my signature in presence of two witnesses.

JOEL SIMPSON BLACKBURN.
